UNITED STATES PATENT OFFICE.

ANTONY SILVENE, OF VICTORIA, BRITISH COLUMBIA, CANADA.

AUTOMATIC AIR BRAKE.

Application filed March 31, 1923. Serial No. 629,162.

To all whom it may concern:

Be it known that I, ANTONY SILVENE, citizen of the Dominion of Canada, residing at Victoria, in the Province of British Columbia, Canada, have invented certain new and useful Improvements in Automatic Air Brakes, of which the following is a specification.

This invention relates to an automatic air 10 brake which is designed to dispense with the customary triple valve which controls the delivery of air from the auxiliary reservoir to the brake cylinder and from the brake cylinder to the atmosphere as the pressure of 15 the train pipe is reduced or restored.

It is of that class wherein air under pressure is normally maintained in the train pipe and on both sides of the piston of the 20 brake cylinder and in the auxiliary reservoir of each vehicle of a train, and the brake is applied by a reduction of pressure in the train pipe and in the space of the cylinder on one side of the piston, whereby the air 25 on the other side of the piston, which is in communication with the auxiliary reservoir, expands to move the piston outward and apply the brake.

The invention is particularly described in the following specification, reference being made to the drawings by which it is accompanied, in which:

Fig. 1 is a longitudinal section of the brake cylinder and the auxiliary reservoir.

Fig. 2 is a similar view showing a modification of the smaller piston, and

Fig. 3 is a longitudinal section of a supplementary air exhaust valve.

Fig. 4 is a modification in which the cylinder cover is recessed into the cylinder.

In these drawings 2 represents the brake cylinder, to the after end of which is secured an auxiliary reservoir 3 in full communication with the end of the cylinder to which it is connected. To the opposite or forward 40 end of the cylinder 2 is secured a cover 4 from which a cylinder 5 projects in axial alignment with 2. This cylinder 5 is of relatively 45 smaller diameter than the brake cylinder 2 and its length approximately corresponds therewith.

The cover of the cylinder 4 has an annular projection within the diameter of the cylinder 5, in the outer side of which projection is seated a leather or fibre washer 6.

A piston 8 is endwise movable within the 55 cylinder 2 having a piston rod 9 secured on its inner end, which piston is provided with two oppositely turned cupped leather packing rings 10. A piston 11 is secured on the rod 9, at such distance from the 60 piston 8 that when that piston is at the inner limit of its movement toward the reservoir 3 a V-shaped annular projection 12 on the piston 11 will seat on the washer 6.

Every care should be taken to make its 65 piston 11 air-tight, preferably, as shown in Fig. 2, with a cupped leather 13 and a packing ring 14.

Between the piston 11 and the end cover 15 of the cylinder 5, a coiled spring 16 is 70 introduced that will normally maintain the pistons 8 and 11 at the inner limit of their movement, as shown in Figs. 1 and 2.

Air is delivered into the forward end of the cylinder 2 from the train pipe 20 75 through a branch pipe 21, connected to the cover 4 of that cylinder. The pressure of this air acting on the area of the piston 8 will move that piston and its connected parts to the inner limit of its movement and 80 will withdraw the brake blocks from the wheels of the vehicle.

At the inner limit of the backward or release movement of the piston 8 the air passes through a feed groove 22 provided past 85 the piston in the bore of the cylinder and charges the auxiliary reservoir 3.

If the brake is applied to a freight car, where there is liable to be any considerable difference between the weight loaded and 90 empty, or to an exceptionally heavy vehicle, a secondary reservoir 23 may be provided to which the air passes from the reservoir 3 through a pipe 24 and stop-cock 25.

When the train pipe 20 is charged with 95 air under pressure from the main reservoir on the engine, as when the train is running, the train pipe 20, being in direct communication with the cylinder 2 and reservoir 3, that air pressure is also maintained on both 100 sides of the piston 8 in the brake cylinder 2 and also in the auxiliary reservoir 3, and in the secondary reservoir 23, if such is provided, but is prevented passing into the cylinder 5 by the seat of the annular V-shaped 105 ridge of the piston 11 on the leather or fibre washer 6.

When the pressure in the train pipe 20 is

reduced either by its release through the driver's brake valve on the engine, or through separation of the couplings of the train pipe, as in the case of a break-away, 5 the air is withdrawn from the forward side of the piston 8 in the cylinder 2 and the air of the auxiliary reservoir, expanding into the cylinder 2 on the other side of the piston 8, that piston is moved outward to apply the 10 brake, with a pressure, dependent on the reduction made in the train pipe and the volume of the piston's movement in the cylinder 2 in relation to the volume of the reservoir 3, acting on the available area of 15 the piston 8.

When the pressure in the train pipe 20 is restored, that pressure, acting on the front side of the piston 8, moves it to the backward limit of its movement, returning the 20 air to the auxiliary reservoir 3 and restoring its pressure through the groove 22, and seating the piston 11 on the washer 6.

To enable the air within the cylinder 2 in front of the piston 8 to escape more quickly, 25 as when an emergency stop is required, a cup piston 26, endwise movable within a small cylinder 27, is introduced in the branch pipe 21, through which communication is made from the train pipe 20 to the cylinder 2. This cup piston has a central aperture 28 through which air may pass to or from the cylinder 2, and the piston is held by a spring 29 at the inner limit of its movement 30 toward the cylinder 2 covering exhaust ports 30 in the body of the cylinder 27.

Air may pass freely from the train pipe 20 to the cylinder 2 through the aperture 28 of the cup piston, and during moderate reduction of pressure in the train pipe may 40 pass outward from the cylinder through the same aperture, but if a sudden reduction of pressure is made in the train pipe 20, as for an ordinary stop, the air being unable to escape from the forward end of the cylinder 2 with sufficient freedom, the cup piston 26 will move outward against the resistance of the spring 29, and will uncover the ports 30 to provide free escape of the air from the cylinder.

The several parts of this brake are simple and not liable to derangement, and in applying the brake a reduction of pressure in the train pipe will more directly be a measure of the pressure on the several pistons, and will not be subject to the erratic actions which the well known triple valve is subject to.

Figure 4 shows a modification wherein the cover is recessed into the end of an existing cylinder.

Having now particularly described my invention, I hereby declare that what I claim as new and desire to be protected in by Letters Patent, is:

1. An automatic air brake, comprising

the combination with a brake cylinder, an auxiliary reservoir connected to one end of the cylinder to be in direct communication therewith, a cover on the opposite end of the brake cylinder, a piston endwise movable in the brake cylinder, a rod connected to the piston and passing axially through the cover, a spring normally holding the piston of the brake cylinder at the backward limit of its movement therein toward the reservoir, means on the piston rod for air sealing it on the cover when the piston of the brake cylinder is at the backward limit of its movement therein, means for delivering air directly from the train pipe to the forward end of the brake cylinder, and means for passing air from the forward side of the piston to the opposite side of the same.

2. An automatic air brake, comprising the combination with a brake cylinder, an auxiliary reservoir connected to one end of the brake cylinder to be in direct communication therewith, a cover on the opposite end of the cylinder, said cover having a cylinder of relatively less diameter than the brake cylinder and approximately the same length projecting outwardly from it in axial alignment with the brake cylinder with an inwardly projecting collar between it and the brake cylinder, a piston endwise movable in the brake cylinder, a piston endwise movable in the cover cylinder, a rod axially connecting the two pistons and projecting through the end of the cover cylinder, means normally holding the pistons at the backward limit of their movement toward the reservoir with the piston of the cover cylinder seated air-tight on the collar between the two cylinders, means for delivering air directly from the train pipe to the forward end of the brake cylinder, and means for passing air from the forward side of the piston of the brake cylinder to the reservoir side of the same when the piston is at the backward limit of its movement.

3. An automatic air brake, comprising the combination, with a brake cylinder, an auxiliary reservoir connected to one end of the brake cylinder to be in direct communication therewith, a cover on the opposite end of the cylinder, said cover having a cylinder of relatively less diameter than the brake cylinder and approximately the same length projecting outwardly from it in axial alignment with the brake cylinder with an inwardly projecting collar between it and the brake cylinder, a piston endwise movable in the brake cylinder, a piston endwise movable in the cover cylinder, a rod axially connecting the two pistons and projecting through the end of the cover cylinder, means normally holding the pistons at the backward limit of their movement toward the reservoir with the piston

of the cover cylinder seated air-tight on the collar between the two cylinders, means for delivering air directly from the train pipe to the forward end of the brake cylinder, means for passing air from the forward side of the piston of the brake cylinder to the reservoir side of the same when the pis-

ton is at the backward limit of its movement, and means in the train pipe connection for exhausting air from the brake cylinder when the pressure of the air is reduced in the train pipe. ¹⁰

In testimony whereof I affix my signature.
ANTONY SILVÈNE.
